UNITED STATES PATENT OFFICE

JAMES MADISON MEREDITH, OF LEWIS, IOWA

CLOTHESLINE TIGHTENER

Application filed October 11, 1928. Serial No. 311,914.

This invention relates to clothes line devices and pertains particularly to a tightening device or attachment for a line by means of which the line may be maintained in a taut condition.

The present invention has for its primary object to provide a device for holding a clothes line tight and to increase its holding or tightening action upon the line in proportion to the weight applied thereto.

A further object of the invention is to provide a device for holding a clothes line in tight condition both when clothes are hung on the line and when the line is empty, the device being of simple but strong and durable construction and comparatively inexpensive to produce.

The invention broadly contemplates the provision of an upright bar and supporting means therefor whereby it may be pivotally mounted intermediate its ends upon a suitable supporting structure such for example as a post or building wall, the bar being designed to have a clothes line secured to the lower end thereof and a spring secured at one end to the upper end thereof, the other end of the spring being secured to the line at a point a substantial distance forward of the attached end of the line. The distance between the point of support of the bar and the point where the line is attached is materially less than the distance between the point of support of the bar and the upper end or the end where the spring is connected so that when weight is applied to the line the lower end of the bar will be swung toward the line while the upper end will be pulled away therefrom thus acting to pull upon the spring member which in turn exerts a pull upon the line which tends to pull it tight.

The invention will be best understood from a consideration of the following detailed description taken in connection with the accompanying drawing forming a part of this specification, with the understanding, however, that the invention is not confined to any strict conformity with the showing of the drawing but may be changed or modified so long as such changes or modifications mark no material departure from the salient fea-

tures of the invention as expressed in the appended claims.

In the drawing:

Figure 1 is a view in side elevation of the clothes line tightener embodying the present invention showing the same applied;

Figure 2 is an enlarged side elevational view partly in section of the device;

Figure 3 is a detailed view of the clamp connecting the line to the spring of the device.

Referring to the drawing in detail, the numeral 1 designates a supporting structure which, while in the present instance is shown as a post may of course be a wall or other suitable structure. Attached to the support is a suitable bracket such as the hook 2 to which is attached a clevis 3. This connection of the clevis with the bracket or hook may be loose so that it may be removed as desired.

Pivottally attached to the clevis 3 is an upright bar 4, the connection being made preferably adjacent the lower end of the bar so that a greater portion thereof extends above the clevis than below.

The lower end of the bar is suitably formed to have one end of a clothes line 5 attached thereto as for example the bar may be provided with the transverse aperture 6 through which the end of the line may be passed to facilitate tying the line to the bar.

A relatively long coil spring 7 is provided, one end of which is connected with the yoke portion of an inverted substantially U-shaped bracket 8 which bracket is secured to the line 5 by passing the line between the legs thereof and drawing the legs together to grip the line, by tightening up the nut 9 upon the bolt 10 which is passed through and connects the legs.

The other end of the spring 7 has a chain 11 connected at one end thereto, this chain being designed to be attached to the pointed upper end 12 of the upright bar 4 by engaging one of the links thereof over the pointed end of the bar.

From the foregoing description it will be readily apparent that when a clothes line is attached at one end to the lower end of the bar in the manner shown and weight applied

thereto the said lower end of the bar will be caused to swing about the pivot pin 13 by which it is secured to the holding clevis 3 toward the line. This swing of the relatively short lower end of the bar will produce a greatly increased swing of the upper end of the bar thereby pulling on the spring 7 and causing it to exert an upward pull upon the line 5 to maintain the line tight.

Having thus described my invention what I claim is:

10. 1. A clothes line tightener comprising an elongated resilient member having means for the attachment at one end to a line, and pivotal means carrying and connected to the other end of said member and to the line whereby upon the application of a downward pull to the line a pull will be directly transmitted to the said other end of the resilient member, placing the same under tension to oppose the downward pull on the line.
15. 2. A clothes line tightener, comprising an upright member pivotally mounted intermediate its ends, means for connecting a line to the lower end of the member, and an elongated resilient member having means for attachment at one end to the line and having its other end connected to the upper end of the upright member.
20. 3. A clothes line tightener comprising a normally upright bar, means for pivotally mounting said bar at a point adjacent the lower end, means for securing a clothes line to the lower end of said bar, an elongated resilient member, means for connecting one end of said member to said clothes line, and means for connecting the other end of the resilient member to the upper end of the bar.
25. 4. A clothes line tightener comprising a normally vertical bar, means for pivotally supporting the bar at a point adjacent the lower end, means for attaching one end of a clothes line to the lower end of the bar, an elongated spring body, a clamp carried at one end of the spring for engaging said line, and a chain connected to the other end of the spring and adjustably connected to the upper end of the bar.
30. 5. A clothes line tightener, comprising a pivotally mounted member having means for attachment at one end of a line, and means associated with the member and line to tighten the line upon application of a downward pull thereto.
35. 6. A clothes line tightener, comprising a pivotally mounted member having means for attaching a clothes line to one end thereof, and means connecting the other end of the member with the line whereby the line will be drawn taut upon application of a downward pull thereto.

JAMES MADISON MEREDITH.
